H. C. LONG

ATTACHMENT FOR DOOR FRAMES

Filed Jan. 19, 1924

Inventor
HENRY C. LONG

Ch. F. Parker
Attorney

UNITED STATES PATENT OFFICE.

HENRY C. LONG, OF WEST HARTFORD, CONNECTICUT.

ATTACHMENT FOR DOOR FRAMES.

Application filed January 19, 1924. Serial No. 687,243.

To all whom it may concern:

Be it known that I, HENRY C. LONG, a citizen of the United States, residing at West Hartford, in the county of Hartford, 5 and State of Connecticut, have invented certain new and useful Improvements in Attachments for Door Frames, of which the following is a specification.

This invention relates to door frames, and 10 more particularly to an extensible attachment to take up space between the frame and the door.

An object of the invention is the provision of a resilient device that will automatically 15 adjust itself to the space between the door and door frame caused by a shrinkage or drawing of the door due to changes in temperature.

A further object is the provision of a device 20 of this character which may be readily attached to the door frame.

In the accompanying drawings, I have shown one embodiment of the invention. In this showing:

25 Figure 1 is a perspective view of a door frame showing the invention applied,

Figure 2 is a front elevation of the attachment removed,

Figure 3 is a horizontal sectional view 30 showing the door closed, and,

Figure 4 is a similar view of the door frame showing the door removed or in open position.

Referring to the drawings, the reference 35 numeral 1 designates a door of the usual construction which is supported on a post 2 by means of hinges (not shown). When the door is in closed position, it is adapted to be arranged opposite a post or a door frame 3.

40 As shown, this member is provided with a cut-away portion for the reception of the door and beyond the cut-away portion, there is provided a door jamb 4. The parts here-tofore described are of the usual construction and form no part of the invention except in the combination claimed.

The attachment consists of a strip of metal having a flat face 5, adapted to be attached to the side of the door frame. As 50 shown, this face is provided with elongated slots 6 for the reception of suitable fastening elements. By providing elongated slots, the device may be adjusted from time to time.

The plate 5 is provided with cut-out portions 7 which permit it to adjust itself to any irregularities in the face of the door frame.

As shown, the plate is adapted to be arranged adjacent the door jamb and is provided with an extension 8 arranged substantially at right angles to the plate and extending inwardly between the door and the door jamb when the door is in closed position (see Figure 3). The inner edge of this extension is offset, forming a flat face or surface 9 adapted to be arranged on the side of the door jamb. This flat face is secured to the door jamb 4 by means of suitable fastening elements 10, which are adapted to pass through elongated slots 11. The face 9 is provided with cut-out portions 12 extending from the outer edge of the face transversely a distance less than the width of the face and the inner ends of this cut-out portion are provided with slits 13 extending the remainder of the width of the face. 75

The operation of the device will be readily apparent from the foregoing description. The device is arranged in position on the door frame and the extension 8 and the inner face 9 normally assumes the position 80 shown in Figure 3 of the drawings. When the door is closed, the outer face of the door engages the extension 8 and due to its resiliency, the extension 8 is moved inwardly. The elongated slots 11 permit the face 9 to 85 move inwardly over the screws 10. This provides means for filling or closing the space between the door and the door jamb, as shown in Figure 3 of the drawings, and the inherent resiliency of the metal strip 90 permits it to accommodate itself to changes in the size of the space without adjustment. If the door should shrink to the extent that an entire adjustment is necessary, the entire attachment may be moved laterally of the 95 door frame by slightly loosening the screws or fastening elements in the slots 6. The cut-out portions 7 and 12 permit the two flat faces to adjust themselves to irregularities in the surfaces over which they are arranged. 100

It is to be understood that the form of the invention herewith shown and described is to be taken as a preferred example of the same and that various changes in the shape, 105 size, and arrangement of parts may be resorted to without departing from the spirit of the invention or the scope of the subjoined claims.

I claim:

1. An attachment for door frames comprising a resilient plate substantially Z-

- shaped in cross section, the parallel faces of said plate being provided with elongated slots, one of said faces being adapted to be secured to the side of the door frame, and 5 the other face being adapted to be secured to the side of the jamb, the edges of said plate being provided with cut out portions to permit it to adjust itself to irregularities in the surface of the door jamb and door frame.
- 10 2. An attachment for door frames comprising a resilient plate substantially Z-shaped in cross section, said plate being provided with elongated slots adjacent each edge for the reception of fastening elements 15 whereby said attachment may be adjusted laterally of the door frame, the edges of said plate being provided with cut-out portions to permit it to adjust itself to irregularities in the surface of the door frame.
- 20 3. An attachment for door frames com-
- prising a resilient plate having a section adapted to be secured to a door frame, the outer edge of said section being provided with cut out portions to permit it to adjust itself to irregularities in the surface of the door frame, said plate being extended laterally and adapted to be arranged over the door jamb and engaged by the face of the door when the door is in closed position, 25 said plate being then extended substantially parallel to said first section and secured to the outer face of the door jamb, the free edge of said last mentioned section being provided with cut out portions to permit it to adjust itself to irregularities in the surface of the door jamb.
- 30 In testimony whereof, I affix my signature.

HENRY C. LONG.
